UNITED STATES PATENT OFFICE.

BENJAMIN F. CALDWELL, OF POMONA, CALIFORNIA.

FURNACE.

1,351,282.

Specification of Letters Patent. Patented Aug. 31, 1920.

Application filed April 21, 1919. Serial No. 291,746.

To all whom it may concern:

Be it known that I, BENJAMIN F. CALDWELL, a citizen of the United States, residing at Pomona, in the county of Los Angeles and State of California, have invented new and useful Improvements in Furnaces, of which the following is a specification.

My invention relates to a furnace, and more particularly to a heating furnace for residences and the like.

An object of my invention is to provide a gas burning heating furnace which may be placed in the cellar of a house and may be employed to heat its various rooms independently.

Another object is to produce a furnace of the character described which is made up of standard heating sections inclosed within an outer casing so that it may be made in various sizes and capacities with little trouble and comparatively small expense.

With these and other objects in view my invention consists of the construction, combination and arrangement of parts herein-after described and claimed.

In the accompanying drawings which form a part of this specification,

Figure 1 is a fragmentary view of the basement of a house showing a furnace embodying the principles of my invention placed therein.

Fig. 2 is an enlarged horizontal section of the furnace taken on the line 2—2 of Fig. 1.

Fig. 3 is a fragmentary view showing the square ends of the valve rods projecting through the floor of a room above the furnace, as seen in the direction indicated by the arrow 3 in Fig. 1.

Fig. 4 is a central vertical section through the furnace taken on the line 4—4 of Fig. 2.

Fig. 5 is a diagrammatic view illustrating the method of assembling the standard heating sections to form a larger furnace than that shown in the other figures.

Referring to Fig. 1, 10 is a house chimney extending upwardly from the basement floor 11 through the floor 12 of the upper room which is laid on joists 13 supported by a cross beam 14, which in turn is supported by upright posts 15 resting on the basement floor. The furnace 16 also rests on the basement floor and has heat conducting pipes 17 extending from the furnace to registers 18 placed in the various rooms of

the house. A smoke pipe 19 connects the furnace with the chimney 10. The furnace proper consists of an outer casing 20 equipped with a dome 21 to which the heating pipes 17 are connected. The interior of the furnace is formed of standard heating sections. A standard burner section 22 is placed in the front end of the furnace, a standard outlet section 23 is placed in the rear end of the furnace and a standard intermediate section 24 is placed between them. These sections are securely fixed in spaced relation to each other by longitudinal top bars 25 and bottom bars 26 between which they are clamped by vertical rods 27 which extend through lugs 28 formed on the heating sections and through said top and bottom bars and have tightening nuts 29 on their upper ends.

The burner section is made slightly larger than the outlet section, and consists of a casing formed of an upper plate 30 and a lower plate 31 approximately semicircular in form between which a vertical sheet of metal 32 is clamped to form the sides. The edges of this casing sheet rest in grooves 30' and 31' formed around the margins of the plates. The upper and lower plates are formed with vertically coinciding holes 33 in which vertical flue pipes 34 have their ends fixed. The lower plate has a large circular opening 35 formed at approximately its middle in which a burner chimney 36 is fixed so that it extends to the floor of the furnace and its upper end terminates somewhat below the upper plate. A smaller hole is formed in the upper plate concentric with the burner chimney in which a vertical sight tube 37 is fixed. This sight tube extends through and somewhat above the dome of the outer casing so that the burner may be observed through it from the floor above.

The outlet section is similar in form to the burner section, having top and bottom plates 38 and 39 with side casing 40 clamped between them. Similar flue pipes 41 have their ends fixed in holes formed in the top and bottom plates. The intermediate section is formed in a manner similar to that of the burner and outlet sections, but has relatively narrow top and bottom plates 42 and 43 with straight sides and rounded ends having a sheet metal side 44 clamped between them. A single row of flue pipes 34, similar to those in the end sections, are fixed in the top and bottom plates of the intermediate section.

mediate section. All of the sections have opposite lugs 28 formed around the top and bottom plates through which rods 27 extend and hold the plates in a clamped position on the side casing.

Horizontal cross flues 46 and 47 extend between the sections to conduct the products of combustion from section to section proceeding from the burner section to the flue 10 section. These flues are formed of a larger pipe section 48 fixed in one section telescoping over a smaller pipe section 49 fixed in an adjacent section. Provision is thus made for any possible expansion and contraction 15 of the sections of the furnace which might cause variations in the distances between said sections. It will be observed that the cross flue pipes 46 and 47 are of different size, and that the larger are placed alternately 20 below and above the vertical center of the sections; while the smaller cross flues are placed alternately above and below, so that there is one larger and one smaller cross flue between each adjacent pair of sections. By this arrangement it will be noted 25 that the products of combustion passing through the furnace from one section to the next will have a tendency to be drawn through the furnace in a sinuous course since the greater draft will be created through the 30 furnace at the ends of adjacent sections having the larger flue connecting the same, and said increased draft being provided between adjacent sections at alternate ends thereof, 35 will cause the greater portion of the products of combustion passing through the furnace to follow the tortuous path of said draft. The heater sections are held in spaced relation from the furnace floor by 40 legs 50 fixed to the under side of the bottom plates.

The front end of the furnace is provided 45 with an arched opening 51 from the outside of the furnace into the combustion chamber 52 within the burner chimney 36. A multiple burner 53 supported on legs 54 is positioned in the center of the combustion chamber. The multiple burner comprises four separate burners connected in pairs, 50 each pair having separate feed pipes 55 and 56 which are connected to a common cross pipe 57, and are controlled by separate supply cocks or valves 58 and 59. The cross pipe 57 is connected to a common supply pipe 60 leading from the gas main. The burner is also provided with a pilot burner 61 connected to the cross pipe 57 by an independent pipe 62 controlled by an independent supply cock 63. The burner thus 55 described is adapted to be shoved through the arched opening 51 into the combustion chamber. This opening serves as an air inlet for air supplied to the burner. The main gas supply cocks of the burner are provided 60 with extension rods 64 which extend up-

wardly through the floor 12 of the room above and terminate in squared ends 65 adapted to be operated by a key. These rod ends terminate slightly below the floor surface and the holes are equipped with collars 66 fixed in the floor. These rods are provided so that gas supply may be regulated from above, thus making it unnecessary to descend to the basement for that purpose. Small levers 67 and 68 are attached to the rods close to the furnace by means of which the gas supply may be regulated in the basement when starting the furnace. A transparent plate 69 is fixed in the floor 12 of the room above in vertical 70 alignment with the sight pipe 37, so that the burner can be observed from the upper room by looking downward through the floor plate and the sight tube when regulating the gas.

In the furnace thus far described, but one intermediate section is used with one burner and one outlet section, this provides a relatively small furnace. If it is desired to make a larger one, it is evident, that the 75 burner and outlet sections may be set farther apart and a larger number of intermediate sections placed between them. A suitable outer casing can then be made for the larger furnace thus constructed as illustrated in Fig. 5.

The operation of the furnace which is shown in Fig. 4 is as follows:

The pilot light is originally started by turning on the supply cock 63 and lighting 100 the pilot through the arched opening 51. The burners are then started by turning the main supply cocks 58 and 59 by means of the levers 67 and 68, or by applying the key to the squared ends 65 of the rods 64. The 105 burner is supplied with air entering the arched opening 51. The burnt gases pass upwardly through the burner chimney 36 and spread within the casing of the burner section passing around and between the flue 110 pipes 34 and heating them, then passing out of the burner section through the cross flues 46 and 47 to the intermediate section again spreading and passing around the flue pipes in the intermediate section, then passing 115 from the intermediate section through the cross flues 46 and 47 to the outlet section, and again spreading around the vertical flue pipes in this section and finally passing out through the smoke pipe 19. The air supply for heating the rooms is drawn through a side damper 70 in the outer casing 20 of the furnace. It passes upwardly between and around the heating sections as well as through the vertical flue pipes 34 and 45 120 of the different sections into the dome 21 of the furnace, and thence through the various heat conducting pipes 17 to the registers 18 in the different rooms. The heavier arrows in Fig. 4 indicate the course of the 125 130

burnt gases through the furnace while the lighter arrows indicate that of the air.

While I have shown the preferred construction of my furnace, as now known to me, it will be understood that various changes in construction and combination of parts may be made by those skilled in the art without departing from the spirit of my invention as claimed.

10 I claim:

A heating furnace comprising an outer casing, a series of heating chambers mounted in bodily spaced relation to each other and to and within the said casing, each of 15 the sections provided with respective top

and bottom forming plates and walls arranged on the respective top and bottom plates to form a unitary section, telescopic flues between the adjacent heating sections at the opposite ends thereof, said flues at 20 the opposite ends of the heating sections being a large and a small flue, respectively, with one pair of flues between the adjacent sections reversely arranged relative to the pairs of large and small flues between the 25 next adjacent sections.

In testimony whereof I have signed my name to this specification.

B. F. CALDWELL.
